Inventor:
Leo Cohen,
By his Attorney, Leo W. Meany

UNITED STATES PATENT OFFICE.

LEO COHEN, OF MOUNT VERNON, NEW YORK.

DETACHABLE INDICATOR FOR MERCHANDISE.

1,397,079.

Specification of Letters Patent.

Patented Nov. 15, 1921.

Application filed June 2, 1921. Serial No. 474,508.

To all whom it may concern:

Be it known that I, LEO COHEN, a citizen of the United States, and a resident of Mount Vernon, county of Westchester, and

5 State of New York, have invented certain new and useful Detachable Indicators for Merchandise, of which the following is a specification.

The object of my invention is to afford 10 simple, inexpensive, but effective means for detachably labeling commercial packages and articles in such manner that details relating thereto are rendered conveniently accessible for observation and reference,— 15 the indicator also being adapted for use as a check to insure the replacement of goods exhausted by sale, etc., and for other purposes hereinafter set forth;—my invention comprising an indicator card and holder there- 20 for, the latter being provided with elastic resilient means for detachably securing it to commercial packages of various sizes and shape, so that the device may be continuously and successively applied to stock mer- 25 chandise held for retail trade.

In the accompanying drawing,

Figure 1, is a perspective view illustrating the application of my detachable indicator to a cylindrical container, the latter being 30 shown in dotted lines;

Fig. 2, is perspective view of my indicator as detachably applied to a rectangular container, the latter being shown in dotted lines;

35 Fig. 3, is a front detail view of the register insert card or label tablet.

Fig. 4, is a transverse section of the insert holder and register tablet, taken upon plane of line 4—4, Fig. 2;

40 Fig. 5, is a top view of the device showing a modification in the form of elastic resilient retaining band.

My improved commodity label and indicator, considered as a unitary device, consists essentially of a memorandum insert 45 tablet T, a holder H, therefor, and one or more elastic resilient bands B, connected with the latter, and by means of which the device may be temporarily and detachably affixed to a package or container C, of goods 50 to be disposed of at retail.

The memorandum insert tablet T, may be made of paper, cardboard, celluloid, or any desired material of appropriate flexible 55 character, and adapted to have imposed on

one or both faces thereof memoranda relating to the commodity inclosed in the package or container C, to which my indicator is to be attached.

The holder H, made of any suitable pliable material, so as to adapt itself readily to the external configuration of the commodity container C, to which it may be applied, and to fit various shapes of such containers, consists essentially of an integument adapted to receive and retain the flexible insert tablet T, for which purpose it is formed with an elongate opening h, at top. It is also formed on its front side with a slight opening h', the edges of which constitute a frame for the face of the tablet T, when the latter is positioned in said integument H.

The elastic resilient bands B, by which the holder H, is temporarily attached to a package, are preferably composed, in whole or in part, of india rubber, but may obviously be otherwise constructed with like result in so far as attachment to the commodity container C, is concerned. Thus in 80 the modification shown in Fig. 5, of the drawings, an elastic resilient retractable spring b, is interposed between flexible ligaments b', b', attached to the integument H,— said contractible spring b, acting as a constrictor to bind the device temporarily to a commodity container C, substantially in the same manner indicated in Figs. 1 and 2, in which rubber bands are presumably used 85 for the purpose.

As indicated in Fig. 3, of the drawings, the face of the indicator tablet T, to be exposed through the frontal aperture in the holder H, may bear data relating to the retailing of the merchandise stored in the 95 package or container C, while the back of the tablet may have imposed upon it information relating thereto of a more confidential character, as may be deemed necessary or expedient.

My detachable indicator is designed for temporary attachment, in practice, to a package or a container the contents of which is to be last disposed of in a series of such articles exposed or set aside for sale. When 105 the salesman reaches this last package or article he detaches the indicator, which then becomes a means of warning and information for effecting the replacement of the goods already disposed of by sale,—the de- 110

tached indicator becoming a tangible notification that may be attented to subsequently, and relieving the clerk or salesman of the necessity of immediately making an entry 5 of the fact. In other words, he does not have to neglect his customer, nor the exigencies of trade, to make the memorandum before he forgets the circumstance, as the detached label or indicator serves the purpose, 10 and insures attention, in due time.

Furthermore the use of my detachable indicator as above set forth obviates the necessity for marking each article of like merchandise in a series thereof selected for 5 immediate sale, as the salesman can always ascertain by a glance at the package so labeled the price thereof, and other facts relating thereto which it may be desirable for him to know and take into consideration.

What I claim as my invention and desire 20 to secure by Letters Patent is,

A detachable temporary indicator for commercial packages of the character designated, comprising a flexible memorandum insert tablet, a pliable holder for said flexible insert tablet formed with a frontal sight aperture, an elastic resilient band connected and coincidental with the upper edge of said holder, and an elastic resilient band connected medially with the side edges of said 25 holder and adapted to temporarily and detachably secure the device to commodity containers of various shapes, substantially as and for the purpose described.

LEO COHEN.
